(57) CLAIM

The design for a portable data storage drive, as shown and described.

DESCRIPTION

FIG. 1: is a perspective view of a design for a portable data storage drive according to the present invention;

FIG. 2: is a front view thereof;

FIG. 3: is a rear side view thereof;

FIG. 4: is a left side view thereof;

FIG. 5: is a right side view thereof;

FIG. 6: is a top plan view thereof; and,

FIG. 7: is a bottom plan view thereof.
